UNITED STATES PATENT OFFICE.

FRANK T. CORTESE, OF BROOKLYN, NEW YORK.

DESIGN FOR A COMBINED PAPER WEIGHT AND INKWELL.

Application filed August 31, 1925. Serial No. 14,666. Term of patent 7 years.

To all whom it may concern:

Be it known that I, FRANK T. CORTESE, a citizen of the United States, residing at Brooklyn, in the county of Kings and State of New York, have invented a new, original, and ornamental Design for a Combined Paper Weight and Inkwell, of which the following is a specification, reference being had to the accompanying drawing, forming part thereof.

The figure is a perspective view of a combined paper weight and ink well, showing my new design.

I claim:

The ornamental design for a combined paper weight and ink well, as shown.

FRANK T. CORTESE.
